UNITED STATES PATENT OFFICE.

CHARLES T. OSBORNE, OF NEW YORK, N. Y.

MOTOR.

SPECIFICATION forming part of Letters Patent No. 729,652, dated June 2, 1903.

Application filed September 27, 1901. Serial No. 76,749. (No model.)

To all whom it may concern:

Be it known that I, CHARLES T. OSBORNE, a citizen of the United States, residing in the city of New York, borough of Manhattan, in the county and State of New York, have invented a certain new and useful Improvement in Motors, of which the following is a specification.

The invention relates to motors of the explosive-engine type.

The objects sought to be attained by my improvement are economy of power, economy and convenience in absorbing heat from the explosive-engine, ease of starting the motor, means for conserving surplus energy developed by the explosions, and means for applying the energy thus conserved in temporarily supplying an increase of power. To attain these objects I employ an explosive-engine, preferably using gas or gasoline vapor with air, as the explosive mixture, and provide an air-compressor operated by the engine and a reservoir for the air thus compressed. An air-engine working on the same engine-shaft is driven by the compressed air from the reservoir and is used in starting the motor and while running delivers its exhaust-air at low temperature to a suitable jacket or chamber surrounding the cylinder of the explosive-engine and absorbs heat from the latter. The compressor is also equipped with suitable valves and passages by means of which its function as a compressor may be temporarily suspended and this portion of the mechanism conditioned to act as an auxiliary air-engine driven by the compressed air stored in the reservoir and serving to aid in starting the motor or in overcoming any temporary increase of load or other work to be performed. The products of combustion or exhaust from the explosive-engine are discharged upon, or in the immediate vicinity of the valve-chamber of the air-engine or other portion liable to become too cold. The compressor and air-engine are preferably arranged in close proximity to each other or joined in the same casting, so that the high temperature of one may neutralize the low temperature of the other.

The invention consists in certain novel combinations and arrangements of parts to

be hereinafter fully described, and pointed out in the claims.

The accompanying drawings form a part of this specification and show the manner in which the invention is to be carried out.

Figure 1 is a general plan view, and Fig. 2 is a corresponding side elevation. Fig. 3 is a transverse section, partly in elevation, showing the arrangement of the several cylinders and their immediate connections on a larger scale. Fig. 4 is a horizontal section, on a still larger scale, showing a portion in detail. Fig. 5 is an enlarged sectional view of the automatic diaphragm-valve.

Similar letters of reference indicate the same parts in all the figures.

A is the cylinder of an explosive-engine shown as a gasoline-engine of the four-cycle type and may be of any ordinary or approved construction, equipped with inlet and exhaust valves (not shown) operated by the usual mechanism. A trunk-piston (not shown) inclosed in the cylinder A is driven by the explosion of a suitable mixture of gasoline-vapor and air received from a carburetor B through a pipe B', controlled by an automatic diaphragm-valve B², as will presently appear. Gasoline from a tank B³ is supplied through a pipe B⁴, controlled by a valve to the carburetor, as usual.

The reciprocations of the trunk-piston are converted into rotary motion of the engine-shaft A² through a pitman A³ and crank A⁴, as usual.

A⁵ is a fly-wheel performing its usual functions, and A⁶ is a sprocket-wheel from which power may be taken to drive the desired mechanism.

C is the cylinder of a double-acting air-compressor, having a piston (not shown) and inlet-valves C² C³ and delivering through check-valves C³ C² in a pipe C⁴, leading the compressed air to the upper portion of a suitable reservoir C⁵, located at any convenient point, preferably in an exposed position, subject to the cooling action of the air. The air-compressor is driven by a crank C⁶ on the engine-shaft A², set at a right angle to the crank A⁴ and connected by the pitman C⁷ to the piston-rod C⁸ of the compressor-piston.

F is an air-pump, shown as an ordinary hand-pump, but which will be understood to be any means of compressing air in the reservoir C⁵ independently of the air-compressor

5 C.

- Alongside the compressor-cylinder and parallel therewith and with the cylinder A is an air-engine, comprising the cylinder D, containing a piston (not shown) and having a valve-chamber D², inclosing a reciprocating valve (not shown, but preferably of the double-piston type) controlled and operated through a link-motion D⁴ of the usual form by the eccentric D⁵ D⁵ on the engine-shaft. 10 Air to drive the air-engine is received from the reservoir C⁵ through a pipe D⁶, controlled by a throttle-valve D⁷ and leading to the valve-chamber D² and distributed, as usual. The power thus received from the compressed air 15 is returned to the engine-shaft A² through the piston-rod D⁸, pitman D⁹, and crank D¹⁰, set at a right angle to the crank C⁶ and opposite to the crank A⁴.

E is a pipe leading from the air-reservoir C⁵ to the diaphragm-valve B², which may be a valve held normally open by a spring and closed in opposition thereto by pressure received below a diaphragm, as will be understood.

30 E' is a spring-valve analogous to an ordinary pop safety-valve, holding the pipe E closed, but set to lift and open the passage when the pressure in the reservoir reaches the limit for which the valve is loaded and allow

35 the pressure to be felt by the diaphragm-valve and immediately close the latter and prevent further supply from the carbureter to the explosive-engine until the pressure in the reservoir is sufficiently reduced, by the demands

40 of the air-engine or otherwise, to allow the valve E' to close and the valve B² automatically to open again. Thus it will be seen that the action of the explosive-engine is intermittent when running. The sparking or

45 other igniting device may run continuously, but the explosive mixture is withheld during the intervals in which pressure accumulates in the reservoir for use when required, thus conserving the energy and allowing the fly-

50 wheel A⁵ to be greatly lessened in weight or entirely omitted, the motion and power being maintained by the action of the air-engine.

To aid in starting the motor or for temporarily adding to the power in maintaining speed for short periods under increased load, I equip the compressor with suitable valves and passages, normally idle, permitting its conversion into an auxiliary air-engine driven by the air-pressure in the reservoir.

60 Air under pressure is admitted to the cylinder D of the air-engine through the pipe D⁶, leading from a low point in the reservoir C⁵ to the valve-chamber D², and after performing its work in the cylinder D is exhausted

65 through the pipes G G and G' to the jacket or annular chamber A', surrounding the cylin-

der A, and serves by its extremely low temperature to absorb the heat from the latter. The hot products of combustion from the cylinder A are exhausted through the pipe A⁷ and allowed to escape against the valve-chamber D² and cylinder D, and thus serve in raising the temperature of these parts. 70

When the compressor is to be used as an auxiliary engine, air under pressure is introduced as follows: C⁹ is a valve-chamber containing a double-piston valve (not shown) similar to the valve for the air-engine, and L is a pipe leading from a low point in the reservoir C⁵, or the pipe D⁶ therefrom, to a two-way valve H in the pipe C⁴, and thence to the valve-chamber C⁹, and is distributed as usual. The two-way valve H is adapted when in one position to close the pipe L, while allowing free passage for the air delivered by the compressing operation, and when in the other position (see Fig. 4) to close the pipe C⁴ and open communication through the pipe L between the reservoir and valve-chamber C⁹. Thus conditioned the compressor serves as an 80 air-engine and is controlled by a link-motion J and eccentric J' J', corresponding to the same parts for the air-engine D. The exhaust escapes through the pipes K K and K' to the pipe G, leading from the valve-chamber of the 85 engine D, and delivering through G' to the jacket A'.

G² is a valve in the pipe K' kept normally closed but to be opened when the compressor is to be used as above. 90

The operation of the motor is as follows: Air-pressure in the reservoir C⁵ is raised, in the first instance, by the hand-pump F or by other independent means and is admitted to the cylinder D of the air-engine by turning 105 the throttle-valve D⁷. If the load be light, the shaft A² will turn over; but if for any reason it refuses the valve G² is opened and the two-way valve H turned to admit compressed air to the compressor, now acting as an auxiliary air-engine, and the shaft A² is caused to rotate. The ignition device for the explosive-engine being set in operation, the latter is immediately started and exerts its force to continue the rotation. The two-way valve H is 110 then turned to shut off the air from the compressor and allow it to perform its compressing function, and the exhaust-valve G² is also closed to shut off the exhaust-passage. The explosive-engine continues to run effectively 115 until the pressure in the reservoir rises sufficiently to lift the loaded valve E' and through the diaphragm-valve B² automatically cut off the supply from the carbureter, as before described. The motor will now run under the 120 air-engine alone until the pressure again falls and the explosive-engine resumes its work. If for any reason it is desired to increase the power for a short period, the compressor may be converted into an auxiliary air-engine, and 125 thus run until the pressure is insufficient.

M is a safety-valve on the reservoir, adapted

to lift at a pressure above that at which the valve E' is set and serves to guard against accident.

I prefer to make the cylinders C and D and their valve-chambers C⁹ and D² in a single casting, for the reason that the high temperature due to compression in the cylinder C will by the conductivity of the metal be neutralized by the low temperature of the cylinder D, due to the expansion of the air therein. These parts may, however, be made in separate castings, joined together or arranged as nearly as practicable to each other. The explosive-cylinder A also may be a part of the same casting, if preferred, or be set nearer the others than here shown, or it may be otherwise arranged in respect thereto.

The improved motor is intended more especially for service in motor-vehicles and similar situations in which it is inconvenient or impracticable to supply water or other cooling agent in sufficient quantities to keep the temperature of the explosive-engine at the required low point.

25 An important advantage attained is the ease with which the motor may be started. So long as there is sufficient pressure in the reservoir the few turns required to condition the explosive-engine for service may be readily made.

30 By storing the surplus energy of the explosive-engine in the form of compressed air capable of being returned as power I am able to lighten the construction, notably in the heavy fly-wheel usually required, which in 35 my improved motor may be much reduced in weight and in some cases entirely omitted, and in the reduced weight of the frame, which, as the shock of the explosions is virtually received on an air-cushion, is subjected to less 40 violent strains and need not be as substantial as usual in motors of this class.

The explosive-engine having a reserve of power may also be made smaller for work on motor-vehicles and analogous duties, as most 45 power is used in starting and in climbing grades, in which the air-engines may be called upon to assist the explosive-engine.

When used in a motor-vehicle, the energy usually wasted in running idly down grades 50 may with my improved motor be saved and stored in the form of compressed air to be again used. The motor thus conditioned acts as a brake in controlling the speed of the vehicle.

55 The link-motions D⁴ J indicated may be the ordinary Stephenson link valve-gear, and, as will be readily understood, the reversing thereby of the air-engine and the compressor when serving as an auxiliary air-engine necessarily reverses the explosive-engine also.

Modifications may be made in the forms and proportions within wide limits and in the arrangement and location of the parts without departing from the principle of the 65 invention or sacrificing its advantages.

It will be understood that the explosive-engine is provided with a sparking or other

igniting device, and generally all the required equipments, omitted or not specifically described, are of any ordinary or approved 70 construction.

The exhaust from the explosive-engine may be led elsewhere than here shown, especially if the arrangement of the neighboring cylinders be such as to absorb sufficient heat 75 from the compressor and explosive-engine by conduction and radiation.

The reservoir should be so placed as to be exposed as much as possible to the cooling effect of air-currents, so as to reduce the 80 temperature of the compressed air as low as may be.

Although I have described the invention as applied to a gasoline-engine and have described the fluid compressed in the reservoir 85 as atmospheric air, it will be understood that any internal-explosion engine may take the place of the gasoline-engine and the fluid to be compressed and reexpanded may be any elastic fluid—as, for instance, ammonia-gas 90 or carbon dioxid.

I claim—

1. In a motor, the combination of an explosive-engine, an air-compressor driven thereby and having normally idle valves and passages enabling said compressor to run as an engine, an air-reservoir receiving air from said compressor, an air-engine aiding said explosive-engine and driven by compressed air from said reservoir, all connected directly 95 to the same crank-shaft and a two-way valve and its connections to said reservoir, substantially as and for the purpose specified.

2. In a motor, the combination of an explosive-engine, an air-compressor driven thereby and having normally idle valves and passages enabling said compressor to run as an engine, an air-reservoir receiving air from said compressor, an air-engine aiding said explosive-engine and driven by compressed air from 100 said reservoir, all connected directly to the same crank-shaft and a two-way valve and its connections to said reservoir, and means for delivering the cold air from both of said air-engines to said explosive-engine to absorb 105 heat from the latter.

3. The combination of an explosive-engine, an air-compressor, and an air-reservoir, a supply-pipe for said explosive-engine, a self-opening valve B² controlling said supply-pipe 110 and having a valve-operating diaphragm, a pipe E leading from said air-reservoir to the upper face of said diaphragm, and a loaded valve E' controlling said pipe E, whereby pressure in said reservoir when sufficient to 115 lift said loaded valve will by such action be communicated to said self-opening valve and arrest the flow through said supply-pipe.

4. In a motor, the combination of an explosive-engine, an air-engine, an air-compressor 120 having normally inert valves and passages directly connected to the same crank-shaft, said normally inert valves and passages enabling the compressor to run as an auxiliary 125

- engine, a compressed-air reservoir and connections therefrom to said air-engines, means for discontinuing the operation of said explosive-engine, and for reversing said air-engines, 5 whereby the said shaft may be turned temporarily in the reverse direction by the air-engines alone.
5. In a motor, the combination of an explosive-engine, an air-engine, an air-compressor 10 having normally inert valves and passages directly connected to the same crank-shaft, said normally inert valves and passages enabling said compressor to run as an engine, a compressed-air reservoir and connections 15 therefrom to said air-engines, means for discontinuing the operation of said explosive-engine, and means for reversing said air-engines, whereby the said shaft may be turned temporarily in the reverse direction by the 20 air-engines alone, and pipes G, G and G' from the exhaust side of said air-engines to the

cylinder of said explosive-engine, whereby the expanded air may be delivered to said explosive-engine to cool the latter.

6. In a motor, the combination of an explosive-engine, an air-compressor, a reservoir for the compressed air, an air-engine operated by compressed air from said reservoir, the said explosive-engine, compressor and air-engine all directly connected to the same crank-shaft, 25 a valve-gear for said air-engine whereby the said air-engine may be driven either in the same direction as, or in opposition to said explosive-engine and the rate of speed of said crank-shaft thus controlled. 30

In testimony that I claim the invention above set forth I affix my signature in presence of two witnesses.

CHARLES T. OSBORNE.
